UNITED STATES PATENT OFFICE.

THOMAS BINNIE RALSTON, OF BOTHWELL, COUNTY OF LANARK, SCOTLAND.

TARGET AND INDICATING DEVICE THEREFOR.

SPECIFICATION forming part of Letters Patent No. 381,028, dated April 10, 1888.

Application filed January 3, 1888. Serial No. 259,591. (No model.) Patented in England August 22, 1887, No. 11,423.

To all whom it may concern:

Be it known that I, THOMAS BINNIE RALSTON, a citizen of the United Kingdom of Great Britain and Ireland, residing at Bothwell, in the county of Lanark, Scotland, have invented new and useful Improvements in and Relating to Targets for Rifle Practice; and I do hereby declare that the following is a full, clear, and exact description of the invention, which will enable others skilled in the manufacture or art to which it relates to make and use the same, and that the said improvements have been patented to me in Great Britain on the 22d day of August, 1887, by Letters Patent numbered 11,423.

This invention relates to targets for rifle practice of the class in which the part of the target whereon the values are indicated is capable of being moved or swung down in rear of the marker's mantelet for patching purposes or for painting out shot-marks. With such targets as hitherto constructed it is necessary to excavate a trench or space behind the marker's mantelet for the reception of the target when brought down, or to erect protecting mounds or butts of considerable height.

The present invention has partly for its object to so carry and operate the target that, while it is equally applicable where a trench, excavation, or protecting mounds or butts can be had, it is better adapted than formerly for use on flat ground.

The invention has further for its object the provision of improved arrangements for signaling the value of the shot in conjunction with such targets.

On the accompanying drawings, Figure 1 is a front elevation of the improved target in its raised or highest position. Fig. 2 is an elevation with the target lowered. Fig. 3 is an elevation looking from the end marked X, Fig. 1. Fig. 4 is a plan of the apparatus.

In carrying the invention into practice I secure the target or surface A, which is to be shot at, and which is preferably made of stretched canvas, upon a rectangular or other frame, B, which is in its turn bolted or otherwise secured to a frame, C, centered upon a shaft, D, extending horizontally rearward at right angles to the plane of the target. The shaft D is supported upon vertical standards E, which, at

their lower ends, are bolted, clamped, or otherwise secured to a base, F, struts or braces G being employed in addition to the said connection when necessary to give extra stiffness or rigidity. The lower arm or part of the frame C has an adjustable back balance-weight, H, pinned to it, and it is also furnished with a catch, a, Fig. 3, with which a hook or latch, b, formed on the forward end of a lever, c, engages to maintain the target A in its raised position. The lever c is centered upon one of the vertical standards E, and instead of being a hand-lever, as shown, it may have a treadle at its end nearest the marker, or be otherwise so arranged that it can be operated by his foot when it is desired to release the target A.

When the target has been struck and it is desired to patch it or to obliterate the value of the shot, the lever c is so operated as to release the hook or latch b from the catch a, which being done, the target, overcoming the counterpoise H, swings downward in the direction of the arrow, Fig. 1, through a quadrant, and until another catch, d, on the frame C comes opposite and is caught by the hook of the lever c, the target being then behind the marker's mantelet and in the position shown by Fig. 2, when it may be patched or have the mark of the shot otherwise obliterated. This being done, the lever c is again operated to release its hook or latch from the catch d, when the counterpoise weight H swings the target partially upward, the raising of it to its vertical or firing position being completed by the marker taking hold of the frame C or other convenient part.

To signal the value of the shots, there is provided, in conjunction with the target, an improved indicating arrangement consisting of a frame, I, mounted upon a shaft, J, which is laid parallel to the shaft D and supported by the standards E, the shafts D and J being geared together at one end by spur-wheels f. The frame I has an adjustable counterpoise-weight, K, and it also carries on a rod or spindle, g, two smaller frames, L M, the normal position of which is at right angles to the frames I and C—that is to say, parallel to the shafts D J. The frames L M, which are filled in so as to present solid flat surfaces, have their opposite sides painted different colors,

and the colors of the frame L are different from those of the frame M, the four colors indicating the four several values of a shot on the target.

- 5 Each frame L M has connected to it two springs, *h i*, the action of which is to maintain the frames in their normal positions. When the target A has been struck, one of the frames L M is turned against the action of its springs 10 until it lies parallel with the frame I, and presents in the direction of the marksman its side having the color indicative of the value of the shot, in which position the said frame L or M is held by any suitable catch. This operation 15 is performed previous to swinging down the target, as before set forth, so that immediately the target is swung down the frame I rises to the position shown by Fig. 2 and indicates the value of the shot to the marksman.
- 20 Instead of the indicating apparatus hereinbefore described, the signals may be made with ordinary hand-disks, or with other convenient indicators.

Having now particularly described the invention, what I desire to claim and secure by Letters Patent is—

1. In a target for rifle practice, the combination, with the frame carrying the target and pivoted to a standard, of a lever mounted on 25 the standard, and projections, substantially as described, on the frame, adapted to be engaged by said lever for maintaining the said frame in elevated or lowered position, as set forth.
2. In a target for rifle practice, the combination, with the swinging frame mounted on 30 a standard and having projections *a d*, of a

lever fulcrumed on the standard for engaging said projections, and a counterpoise mounted on the frame for controlling its movement, substantially in the manner set forth. 40

3. In a target for rifle practice, the combination, with two frames swinging across the line of fire and each mounted on a shaft supported on a standard, of gear-wheels secured on said shafts and intermeshing, whereby said 45 frames are made to move simultaneously, as and for the purpose set forth.

4. In a target for rifle practice, the signaling-frame I, furnished with two swinging indicating boards or disks, L M, lying normally 50 at right angles to the frame and capable of being turned and held parallel with it, the said frame being also provided with a counterpoise, K, which when the frame is released from its lowered position swings it partially upward, 55 substantially as described.

5. In a target for rifle practice, the combination of a target-frame and a signaling-frame pivoted on a standard and connected together to operate reciprocally at the same time by 60 means of intermeshing gear-wheels mounted on said frames, substantially in the manner herein set forth.

In witness whereof I have hereunto set my hand and seal this 10th day of December, 1887.

THOS. BINNIE RALSTON. [L. S.]
